C. A. STUART

BEDSTEAD END FRAME

Filed Sept. 12, 1925

Inventor

Charles A. Stuart

By Fisher, Towle, Clapp & Crane
Attorneys

UNITED STATES PATENT OFFICE.

CHARLES A. STUART, OF KENOSHA, WISCONSIN, ASSIGNEE TO SIMMONS COMPANY,
OF NEW YORK, N. Y., A CORPORATION OF DELAWARE.

DESIGN FOR A BEDSTEAD END FRAME.

Application filed September 12, 1925. Serial No. 14,762. Term of patent 14 years.

To all whom it may concern:

Be it known that I, CHARLES A. STUART, a citizen of the United States, and a resident of the city of Kenosha, county of Kenosha, and State of Wisconsin, have invented a new, original, and ornamental Design for Bedstead End Frame, of which the following is a specification, reference being had to

the accompanying drawing, forming part thereof.

The figure is a perspective view of a bedstead end frame embodying my invention.

I claim:

The ornamental design for bedstead end frame, as shown.

CHARLES A. STUART.
